UNITED STATES PATENT OFFICE.

WILLIAM A. HARTLINE, OF PENNS GROVE, NEW JERSEY.

DESIGN FOR A SERVICE-PIN.

55,039.

Specification for Design.

Patented May 4, 1920.

Application filed July 31, 1918. Serial No. 247,679. Term of patent 14 years.

To all whom it may concern:

Be it known that I, WILLIAM A. HARTLINE, a citizen of the United States, residing at Penns Grove, in the county of Salem and State of New Jersey, have invented a new and original and ornamental Design for a Service-Pin, of which the following is a specification, reference being had to the accompanying drawing, forming part thereof,

The figure is a front elevational view of a service pin, showing my new design.

I claim:

The ornamental design for a service pin as shown.

WM. A. HARTLINE.
